UNITED STATES PATENT OFFICE

ARCHER L. KNAAPP, OF DETROIT, MICHIGAN, ASSIGNOR TO PACKARD MOTOR CAR COMPANY, OF DETROIT, MICHIGAN, A CORPORATION OF MICHIGAN

DESIGN FOR A MOTOR-VEHICLE-RADIATOR CAP

Application filed December 6, 1929. Serial No. 33,679. Term of patent 14 years.

To all whom it may concern:

Be it known that I, ARCHER L. KNAAPP, a citizen of the United States, residing at Detroit, county of Wayne, State of Michigan, have invented a new, original, and ornamental Design for Motor-Vehicle-Radiator Caps, of which the following is a specification, reference being had to the accompanying drawings, forming a part thereof, and in which—

Fig. 1 is a side elevation of a motor vehicle radiator cap showing my new design; Fig. 2 is a front elevation, and Fig. 3 is a top plan view of the same.

I claim:

The ornamental design for a motor vehicle radiator cap, as shown.

In testimony whereof I affix my signature.

ARCHER L. KNAAPP.
